BUTTON

Lon Heron, 7736 N. Eastlake Terrace, Chicago 26, Ill.

Filed Feb. 18, 1958, Ser. No. 715,947

11 Claims. (Cl. 24—103)

This invention relates generally to garment fastening devices and particularly to buttons of the type which avoid the use of conventional connective means.

A satisfactory threadless button fastener or, that is, one which may be applied and removed quickly and conveniently without the need of sewing the same in place or resorting to other types of permanent fastening, has been desired for some time. Such fasteners have particular utility in garments for mental patients or children, for example, who are prone to lose or tear buttons loose from their garments. Other fields of use are also apparent, as for instance, in uniforms or similar garments where the button fasteners must be removed periodically for cleaning and repair purposes. Obviously, if the conventional thread and needle connective system is used in such garments, the labor of removing and replacing the fasteners is burdensome and economically unsound. While the need is particularly felt in such garment classes, all types of clothing for men, women, and children, including outercoats, shirts, pants, suit coats, and like garments in which button fasteners are employed, may conveniently use a fastener which readily may be attached and detached in a quick, convenient and positive manner.

It is to the above-indicated problems and field of endeavor that the present invention is directed. Briefly, the improved fastener of this invention comprises a button body having a recess formed inwardly of its rearward face in which a fastening ring is mounted; the latter including fabric engaging needle prong members. The button is applied by confronting the needle prongs with a portion of the garment fabric and thereafter providing relative movement between the fastening ring and button body to pierce the fabric with the prongs which are thereafter locked in a fastening position. Suitable detent means are included for locking the fastening ring in operative and non-operative positions, so that the same is not accidentally movable. Thus, once the locking ring has been moved to a fastening condition and tightly engaged with a portion of the garment fabric, the same will remain fixed to the garment with little or no relative movement therebetween until the fastening ring is positively reversed to withdraw the needle prongs. In order to promote a pleasing appearance for the button, the operating mechanism of the button is concealed within the button shank, and the outer face of the button body is decorated, as desired. In one form of the invention, movement of the fastening ring is accomplished by engaging the fastening ring with an instrument inserted through the button shank to provide needed relative movement between the same and the button body. Additionally, instruments may be employed to assist inserting the fabric into an interfering position with the needle prongs, although such is not essential to the success of the invention. Modifications of the above briefly described basic button structure are contemplated, including novel means for connecting and associating the fastening ring with the button body and means for a multiple part body to facilitate assembly of the fastening means as well as the provision of decorative qualities and pictorial representations.

The main object of the present invention is to provide a new and improved button fastener which includes

2

quick-acting means for its association and disassociation with fabric.

An additional object of this invention is to provide an improved button fastener, as aforesaid, which carries its own mechanism for connection with fabric.

A still further object of this invention is to provide a new and improved button fastener which may be applied without the use of conventional connective means, such as thread or the like.

Another object of this invention is to provide a new and improved button fastener, as aforesaid, which includes novel aspects of structure and assembly leading to versatility of appearance and use.

Still another important object of this invention is to provide a new and improved button fastener including a mechanical fastening means which operates in a convenient, quick and simple manner and is readily engageable for applying and removing the same from a garment or the like.

20 The above and further objects, features, and advantages of this invention will appear to those familiar with the art from the following detailed description of its features, as found in the preferred and modified embodiments set out in the accompanying drawings.

25 In the drawings:

Figure 1 is a bottom plan view of a button assembly according to the features of the present invention;

Figure 2 is a perspective showing of a fastening ring employed with the button of Figure 1;

30 Figure 3 is a cross-sectional view of the button assembly taken substantially at line 3—3 of Figure 1;

Figure 4 is a side elevational view of my new button assembly showing the same with fabric positioned ready for engagement by the needle prongs of the fastening ring seen in Figure 2;

Figure 5 is an enlarged cross-sectional view taken at line 5—5 of Figure 4;

40 Figure 6 is another side elevational view, similar to Figure 4, showing the fabric engaged by the fastening ring of Figure 2;

Figure 7 is a perspective showing of a tool for rotating the locking ring of Figure 2 relative to the body of the button in order to join the button to fabric, as shown in Figure 6;

Figure 8 is an enlarged plan view, illustrating the operational use of the tool seen in Figure 7;

Figure 9 is a perspective showing of an insert collar member for use in a modified button construction;

50 Figure 10 is a modified button assembly utilizing the insert collar of Figure 9 and the locking ring of Figure 2;

Figure 11 is a view in side elevation with parts broken away in section, showing a second modified button structure;

55 Figure 12 is a front elevational view of the modified buttons of either Figure 10 or 11, demonstrating the use of a pictorial decoration means therewith;

Figure 13 is a top plan view of a third modified button structure;

60 Figure 14 is a mounting tool for placing the fabric in a position for engagement with the rotatable locking ring of the Figure 13 button structure;

Figure 15 is a cross-sectional view taken at line 15—15 of Figure 13 and showing the operation of the tool seen in Figure 14;

65 Figure 16 is a perspective view of another modified button assembly embodying the concepts and features of this invention, parts therein being broken away in section;

70 Figure 17 is an enlarged sectional view taken substantially at vantage line 17—17 of Figure 16 and showing

the internal arrangement of the button assembly with the fastening ring removed;

Figure 18 is a perspective view of a modified fastening ring for use in the button assembly of Figures 16 and 17; and

Figure 19 is an enlarged partial cross-sectional view, similar to Figure 17, illustrating the operational relationship between the several elements of the button assembly including the fastening ring.

Turning now to the features of my invention, as illustrated in the drawings and particularly the first form of button assembly 20, illustrated in Figures 1-8, it will be recognized that such includes a body portion 21 of substantially cylindrical configuration and comprising a head or face end of the button. A shank portion 22 projects integrally from head 21 and terminates in a coaxially disposed cylindrical neck portion 23 of a slightly reduced diameter. The entire body of the button is preferably pressure molded or otherwise formed in a conventional manner of a suitable material, such as "nylon" or thermoplastic materials capable of depicting desired color, shape, and appearance, as is familiar to those versed in the button making art.

The rearwardly extending shank and neck portions 22 and 23 are provided with an annular recess 25 which is undercut at its axially innermost end to flare radially outward, as indicated by numeral 26 in Figure 3. The neck portion 23 is divided at its outer end by a diametrical slotted opening defined by parallel side walls 27, 27 and a transverse bottom wall 28. This slotted opening provides an entry recess for the insertion of fabric or other materials to which the button is to be joined, as will be described in greater detail later herein. Additionally, the slotted opening is cut away at an enlarged arc on one side of the shank portion to provide a recessed surface 29 bordering the annular recess 25 for purposes of operating the locking means of the button, as will be related hereinafter.

The walls of annular opening 25, as best seen in Figure 5 of the drawings, are provided with a pair of arcuately spaced parallel indentations or slots 30 and 31 which extend radially outward from the opening 25 to provide detent recesses for locking a rotatable fastening ring 35 in operative and inoperative positions, respectively.

In addition to the body 21, the button assembly of this invention includes the fastening ring 35 (shown in the perspective view Figure 2) which constitutes a split resilient ring member of spring metal or similar material having opposed ends 36 and 37 which are separated by a gap 38 to permit resilient compression of the ring. Thus, the same may be disposed in the annular opening 25 of the button body 21 by slightly compressing the same. The side wall portion 39 of the locking ring 35 is flared outwardly at its lower edge to form a skirt portion 40 which is received and held in the undercut 26 formed at the inner end of the annular slot 25. Thus, when the compressed locking ring 35 is disposed within the confines of the annular track or opening 25, the outwardly flaring skirt portion 40 enters the undercut 26 and locks the ring 35 against axial displacement.

The substantially cylindrical side wall 39 of the locking ring 35 includes a pair of diametrically opposed upwardly extending arm portions 41, 41 integral with similarly directed tapered needle prong members 42, 42, one formed at the upper end of each arm portion 41 and extending transversely therefrom. From examination of Figure 2, it will be seen that the needle prongs are curved in conformity with the substantially cylindrical formation of the ring 35 and are sufficiently pointed at their outer ends 43, 43 to provide, in conjunction with the tapered body thereof, a penetrating needle capable of readily entering fabric or like material with which the button is to be connected.

The side wall 39 of the locking ring is further provided with an operating notch or recess 45 cut at one

side for cooperation with a pointed finger 46 associated with a mounting tool, indicated generally by numeral 47 and shown particularly in Figure 7 of the drawings. The relationship between the finger 46 and opening 45 will best be understood by examining Figure 8.

A detent projection 50 is also provided on the exterior face of wall 39 of the locking ring substantially opposite the opening 45; the same being adapted to enter and lock with the two recess openings 30, 31.

- 10 When the locking ring 35 is assembled in the annular opening 25 of the button body, the axially outermost end 51 of the side wall 39 substantially coincides with the wall 28 of the transverse slot formed at the outer end of the button shank portion. A bottom wall 52 of the notch 15 45, however, lies flush with the arcuate wall portion 29 which is offset axially with respect to such bottom wall 28. Thus, the finger 46 of the operating tool 47 may enter the recess 45 substantially at the level of the offset wall 29.
- 20 With respect to the operating tool 47, reference is now made to Figure 7 of the drawings from which it will be seen that the same comprises an operating handle portion 60 which has a pair of bifurcated arm portions 61, 61 at its outer end. Such arm portions are defined at their lateral edges by upwardly turned lips 62, 62 flanking opposite sides of a centrally raised or offset platform portion 63 having the operating finger 46 at its outermost end. As shown in Figure 8, for example, the head 21 of the button is adapted to be received on the arm portions 61, 61 between their lips 62, 62, so that the outer face 65 on the button engages the arm portions 61, 61. This position places the prong 46 inwardly of the periphery of the locking ring 35 in the operating notch or recess 45. Thereafter by turning the operating handle 30 60 and holding the button stationary or vice versa, the locking ring 35 may be rotated relative to the body portion to move the locking detent projection 50 thereon, as desired, either to an operating condition, wherein the same resides within the recess 30, or a non-operating condition wherein the same resides in the recess 31.

- 35 As seen in Figures 4 and 6, fabric 65, or the like, to which the button assembly 20 of my invention is to be attached, is suitably creased or folded to provide a projecting portion capable of insertion into the transverse opening formed at the outermost end of the button shank portion and defined by the walls 27, 27 and 28. To facilitate the entry and to hold the fabric fold tightly in this recess while locking the button in place, a needle 66 or like pointed instrumentality may be employed beneath 40 the fabric fold, as desired (see Figures 4 and 6). With the operating ring 35 locked in its non-operating condition, the fabric may readily be inserted into the open recess and positioned for engagement by the needle prongs 42. This condition is best illustrated in Figure 4. 45 If thereafter the tool 47 is employed, as above explained, to rotate the button body relative to the locking ring or vice versa, the needle prongs 42, 42 on opposite side of the locking ring will move across the ends of the recess defined by walls 27, 27 and 28 to pierce and pass through 50 any interferingly placed fold of fabric. This action anchors the button securely in position, as shown in Figure 6, particularly when the needle points 43, 43 pass behind the arcuate wall portions 67 between walls 27 and the opening 25. It will be noted, in this respect, 55 that the needle or other sharp instrumentality 66, which is employed to assist the fabric fold into an interfering position with the needle prongs 42, passes beneath the latter as such is moved to a locked or fastening condition whereat the detent recess 30 and the detent projection 50 are engaged. After the operating ring is locked behind wall portions 67, 67, the needle 66, or other device employed in the manner explained above, is removed. 60 To detach or remove a button of this invention, a mere reversal of the locking procedure is involved as 65 may be accomplished readily by using the operating tool 70 75

47 or a like instrumentality capable of engaging the operating notch 45 to rotate the ring in a reverse direction, thereby freeing the folds of the fabric 65 from the needle prongs 42, 42.

Having thus set forth the features and characteristics of the basic form of button embodying this invention, reference is now made to Figures 9-12 of the drawings wherein a first modified button structure is shown.

As seen in Figure 9, an open-ended insert member 70 of plastic or other resilient material has a first substantially rectangular opening 71 formed through its one side opposite a second larger rectangular opening 72. The opposed end portions of the member are separated by a gap 73 to permit the same to be compressed radially for insertion into a body, as will be related hereinafter. The lower end of the ring 70 is chamfered or undercut at an angle along its inner edge, as indicated by numeral 74. This chamfer cooperates with the outwardly flared skirt portion 40 of the locking ring 35, as shown in Figure 2. The exterior side walls of the ring 70 are generally cylindrical except for an inwardly set annular recess 75 intermediate the ends thereof. Recess 75 cooperates with a projecting annular rib 76 formed in the interior side walls of a substantially cylindrical or annular opening 78 in the shank portion 79 of a modified button 80, seen in Figure 10.

In practice, the fabric engaging fastening ring 35 is inserted inside the insert 70, preferably from the bottom end thereof, so that the chamfered portion 74 mates with the outwardly flared skirt portion 40 on the retaining ring. This structure avoids the undercut 26, used in button 20. The annular sub-assembly, so provided, is then inserted as a unit into the centrally disposed cylindrical bore 78 of the button shank portion, until the projecting rib 76 engages and locks with the detent recess 75 in the insert member 70.

In addition to the modified structure utilizing the annular insert ring 70, the button of Figure 9 may also include a central recess 81 formed inwardly of a front face 82 on the button body portion 83 (see Figure 10). The side walls of such recess 81 are preferably undercut slightly to accommodate a transparent cover member 85 having an outwardly flared edge which, when deformed slightly and pressed into the opening 81, locks in the undercut with snap-in engagement. Cover 85 may be removed, as desired, by including an optional opening 85a at its one edge whereby a prying tool may be inserted therebeneath. It is intended that cover 85 protect and encase a suitable decorative configuration, such as a pictorial representation 87 illustrated in Figure 12. Other forms of decoration also may be used beneath the cover member 85, such as words and phrases, pictures, colors, mottos, flags, and others directed to educational, political, or religious purposes, for example.

Additionally, the cover member 85 may include at least one face having a plurality of parallel ribs and grooves formed therein, so that, as the angles of incidence and reflection are changed with movement of the button relative to the line of sight, one or more pictorial images disposed beneath such a cover member may be observed, either together or one at a time. Although this style of image reproduction is well known in the art, such is felt to be particularly adaptable to the structure of the present button.

In Figure 11, a further modified button 80' is shown having an alternate annular body portion 83' over the periphery of which an annular rim member 90 is mounted with snap-on engagement. Such rim is undercut slightly at one end to provide a first annular lip 91 which mates with a corresponding chamfered face of the body 83'. Rim 90 is also provided with a second chamfered lip portion 92 at its opposite end which is intended to hold the face plate 85' in position over pictorial decoration 87'. The body 83' in turn may have snap-in engagement with an insert shank portion 94 modified to be joined to the annular body 83' by insertion into a

central recess or open center behind picture 87'. An annular detent lip 95 on the insert shank mates with an opposing groove in the body 83' to lock the shank in place. The remainder of the shank portion is substantially as in button 20 of Figure 1, with fabric engaging ring 35 locked in an annular recess formed inwardly of the outer end of the shank portion. The assembly procedure for button 80' is modified somewhat from button 80 of Figure 10, however, since the cover plate 85' is preferably placed within rim 90 and subassembled with body portion 83' for connection therewith as a unit to the insert shank portion 94.

Turning now to the drawing Figures 13, 14, and 15, I have therein shown a still further modified button 100 constructed and operated substantially in accordance with the principles and features of the button 20, hereinabove described, except for certain detail features as will now be amplified.

At the outset, modified button 100 is intended for use primarily on shirts, or similar garments, in which it is desired that the transverse slotted opening formed in the button shank portion for entry, as in button 20 of Figures 4 and 6, be eliminated for the sake of appearance and to prevent puckering of the cloth where the button is joined. With this in mind, modified button 100 is formed with a substantially cylindrical body or head portion 101 which may have a plain or molded face to simulate a conventional shirt button appearance depicting artificial thread passing through opening in the button face, for example. A centrally disposed and rearwardly projecting cylindrical shank portion 102 extends from the body portion 101 and an annular bore 103 is provided concentrically therein, the latter being undercut at its inner end, as indicated at 104, to axially anchor a fastening ring 35, as shown in Figure 2. The ring 35 is compressed radially and thrust into the annular opening 103 until it resiliently locks in place by means of its chamfered skirt portion 40 entering the undercut 104.

A wedge-shaped arcuate opening 105 is formed through the side walls of the button shank portion 102 for insertion of a prong-like tool, indicated at 106, whereby opening 45 of the fastening ring 35 may be engaged to rotate the ring relative to the button body. This action brings the needle prongs 42, 42 thereof into locking engagement with the fabric in the manner previously explained.

To enable the material or fabric to be inserted into opening 103 for engagement by the points of the needle prongs 42, two substantially oval-shaped slots 108, 108 are provided diametrically opposite in the outer wall of annular opening 103. Also the control core of the shank portion is cut away centrally to provide spaced arcuate shaped walls 109 flanking a line passing through the openings 108. This arrangement accommodates the reception of arm portions 108a and 109a of a fabric inserting tool used to assist the installer in forcing fabric within the button shank for engagement by the needle prongs 42, 42. Tool 110 includes a body or handle portion 111 at one end of which extend the spaced fingers 108a and 109a.

Fabric placed across the outer or open end of the button shank portion 102 may be pressed or inserted readily into the openings 108 and 109 to cross the annular opening 103 in front of the needle prongs 42 by means of the insert tool 110. Thereafter, the locking ring 35 may be moved relative to the button body portion 101 to engage the fabric and securely lock the modified button 100 in place; the detent means 50 entering one of the openings 108 to hold ring 35 locked in operating position, as in its cooperation with opening 30, previously described.

Turning now to the features of the modified button assembly 120, illustrated in Figures 16-19 of the drawings, it will be recognized from Figure 16, in particular, that the same includes a substantially cylindrical-shaped plastic body or button head member 121 and a hollow plastic shank member 122 adapted to be inserted into said body

member. A fastening ring 123, illustrated best in Figure 18, is mounted within the interior of the hollow shank member 122 and is held to the body member in a manner to be described presently.

As seen in Figure 17, the body member 121 is provided with a central recess 124 formed inwardly of a rearward face 125 thereof and including a projecting annular bead 126 in its cylindrical side walls. The bottom wall of recess 124 is further formed with a pair of diametrically opposed blind hole openings 128, 128 which are adapted to provide locking engagement with the fastening ring 123 in a manner to be described more fully hereinafter. Additionally, while the face 129 of the button body is shown to be flush, such may be carved or otherwise decorated as by including a snap-in picture cover member, such as 85 of Figure 10.

The projecting bead 126 formed around the periphery of the central depression 124 of the button body is adapted to lockingly engage with an opposing depression 130 formed in the periphery of the shank member 122. Such periphery is defined by a cylindrical outer wall of a substantially circular platform portion 131 which provides the base end of the shank member 122. Substantially frusto-conical side walls 132 extend centrally upward from such platform portion 131 to define the stem or shank of the button. Shank member 122 is further provided with a hollow interior formed by a cylindrical bore 133 which is coaxial with a frusto-conical bore or chamfered section 134 at the axially innermost end of the shank member. The opposite end of bore 133 is also flared outwardly at 135 to provide clearance for fabric when fastening the button. A pair of slotted apertures 136, 136' are formed in the side walls of the cylindrical bore 133 substantially at 90-degree intervals and extending partially along the axial length of bore 133. Slotted openings 136, 136' are for purposes of engaging spring detent means associated with the fastening ring 123, similar to the operation of the detent projection 50 of the previously described ring 35, illustrated in Figure 2 of the drawings. Intermediate said slotted openings and extending outwardly of the cylindrical bore 133 adjacent the outer end of the shank member are a pair of projecting or raised ridges 137 which may be cut away intermediate their ends at 138, as shown, or may include loop openings to cooperate with the fastening ring 123 in locking the same with fabric.

As seen in the cross-sectional showing of Figure 17, the frusto-conical or chamfered portion 134, at the lower end of the shank member, substantially embraces the diametrical dimension defined between the opposed recess openings 128, 128 formed in the button body member. Assembly between the shank member 122 and the body member 121 is accomplished by inserting the platform portion 131 axially into the recess 124 of the body member. When this occurs, the annular raised rib 126 in the periphery of opening 124 engages the opposing peripheral recess 130 in the platform portion 131 to lock the members together. In this manner, the shank member is substantially prevented from axial movement relative to the body member, but, nevertheless, permitted to rotate relative thereto; sufficient clearance being maintained between the diameter of the shank's platform portion 131 and the diameter of the body member's central recess 124 to permit the insertion and movement of the shank member relative to said body.

Referring now to Figures 18 and 19 of the drawings, it will be recognized that a modified locking ring 123, as particularly illustrated in Figure 18, is formed substantially in accordance with the features of ring 35, shown in Figure 2 and heretofore described. It will be noted, however, that the operating opening 45 of ring 35 is absent in ring 123. More importantly two or more locking finger portions 140 depend from the lower edge 141 of an outwardly flared skirt portion 142 provided at the base end of the locking ring 123. The locking ring fur-

ther includes an outwardly extending detent member 144 which lockingly cooperates with the detent recesses 136, 136' of the button shank member 122, as above described.

- 5 In general, ring 123 comprises a substantially open-ended member having opposed ends separated by a gap 145 to permit its resilient radial compression and flexing activity to accommodate movement of the detent projection 144 in and out of the grooves 136, 136', in accordance with the fastening and unfastening procedure for button 120. The fastening ring 123 further includes a pair of oppositely directed and diametrically opposed prong members 146, 146 which are suitably tapered to provide a fabric penetrating point, all in a manner substantially identical to that of the prongs 42 of the previously described locking ring 35.
- With reference now to Figure 19, it will be recognized that the locking ring 123 is shown in its assembled relation with the shank member 122 and the body member 121. In this respect, the depending fingers 140 of the locking ring enter the diametrically opposed blind hole openings 128 formed in the button body member, thereby serving to locate the locking ring and anchor the same against rotation relative to the button body member. Additionally, the openings 128 and the depending fingers 140 are substantially coextensive in cross section to provide a snug fit therebetween. It will be recognized also that shank member 122 surrounds the locking ring 123 and substantially houses the same within the confines of its hollow interior. Note, in particular, that skirt wall 134 closely fits about the flared walls 142, while the lower end of the latter rests firmly on the bottom wall of the recess 124. The circular base 131 of the shank member is preferably maintained free to move relative to the button body and locking ring by provision of an annular clearance or recessed area 150 formed therebeneath inwardly of the bottom wall of recess 124. The side walls of ring 123 also clear the cylindrical bore 133 sufficiently to avoid interference therewith, while prongs 147 and the ridges 137 interfere sufficiently to prevent accidental removal of fabric engaged by the prongs when the button assembly is mounted in position, as will now be described.

With the open end of the shank member 122 placed against fabric and the shank portion positioned so that the locking ring is in a condition wherein the detent means 144 thereof engages the detent slot 136, the button is ready for connection to the fabric. By pressing the fabric inwardly of the open end of the shank, as with the pad of the forefinger or other means, the same is positioned for penetration and engagement with the prong portions 146. Thereafter, relative rotation may be brought about between the shank member 122 and the locking ring by rotating the button body and holding the shank member stationary or vice versa. This latter action is assisted by providing optional serrated teeth 155, or like friction means, at the outer end of the shank member to keep the latter from turning with the button body relative to the fabric with which it is engaged. With the fabric properly aligned in front of the prong members, the latter enter the fabric and provide positive fastening engagement therewith. When sufficient relative rotation between the locking ring and shank portion is provided to dispose the detent means 144 in the recess 136', the outer ends of the prong members will then be aligned in engaging relationship with the raised rib members 137 and particularly will wedge in the cut-out portions 138 thereof. Therefore, cloth engaged by the prongs will be held tightly and prevented from slipping off of the ends of the prong by the presence of the interfering ridges 137. It is also important that the fabric, more or less, provides wedge means between the needle prongs and the inside walls of the shank member to prevent appreciable relative movement between the button and the fabric which might tear or wear the latter.

The modified button 120 has certain advantageous features from an operational standpoint over the previously described forms of the invention, since the same may be mounted by merely pressing the fabric into the open end of the shank and thereafter twisting the button body relative to the engaged shank. Thus, the expedient of employing an operating tool, such as device 60 of Figure 7, may be avoided, if desired.

It will be recognized from the foregoing description that I have hereinabove set forth the features and structural aspects of a new basic form of threadless fastener or button and several modifications. It is believed that those familiar with the art will readily understand and appreciate the merit which marks my present invention as an advancement over prior efforts in this field. Additionally, while I have herein specified and prefer that the body of the button be made of plastic or materials which may be readily molded and configured in any desired shape or form to accommodate desired values of appearance, as taste requires, it is to be understood that other materials may be employed to this end. Further, while the button is illustrated as round, it may take on any desired shape, and materials other than spring metal may be used for locking ring 35 without necessarily departing from spirit and scope of my invention. Consequently, it is not my intention to be limited to the particulars and details of the fastener means, as hereinabove described and set forth in the accompanying drawings, except as may appear in the following appended claims.

I claim:

1. A button fastening device to be joined to fabric which comprises, a body having a hollow shank projecting from one side thereof, the hollow interior of said shank being accessible through one open end thereof, a fastening member mounted in the hollow interior of said shank for rotation relative to the latter, means locking said fastening member against axial displacement, prong means formed on said fastening member and disposed wholly within the axial confines of said shank for engaging fabric inserted into said open end thereof, and means for positively effecting relative rotation between said fastening member and said shank to drive said prong means into said fabric within said shank.

2. The button fastener as set forth in claim 1 including a removable member on the face of said body portion adapted to overlie and protect decorative means, said face member being transparent for the visual dissemination of said decorative means.

3. A button fastener as set forth in claim 1 including detent means for operatively limiting and holding said fastening member at plural preselected positions of rotation relative to said shank.

4. In a button fastener, the combination comprising, a button body, a hollow shank portion on one side of said body having an open end into which fabric may be inserted, a fastening ring rotatably mounted wholly within said shank portion, prong means formed at one end of said ring for engaging fabric within the interior of said shank portion, means locking said fastening ring against axial displacement, and means for selectively rotating said ring and said shank portion relative to each other thereby to drive said prong means into fabric brought into engagement therewith.

5. The combination as set forth in claim 4 including detent means for locking said ring in two preselected positions of rotation relative to said shank portion.

6. The combination as set forth in claim 4 in which said means for causing relative rotation between said ring and shank portion comprises means interconnecting said ring and body, and plural serrations at the outer end of said shank portion for engaging the fabric to hold said shank portion stationary while said ring and body are rotated relative thereto.

7. The combination as set forth in claim 1 including means at the outer end of said shank portion engageable

with the fabric for the purpose of holding said shank portion stationary while said body is rotated relative thereto, and means connecting said fastening member to said body for rotation conjointly therewith.

- 5 8. A button fastener for detachable association with fabric, comprising, a button body having a decorative head portion, a substantially cylindrical shank portion protruding from one side of said head portion, said shank portion having a hollow interior accessible through an open end of said shank portion and an additional opening formed through one side wall thereof, annular fastening means mounted in the interior of said shank portion, means locking said fastening means against axial displacement, means on said fastening means engageable through 10 said additional opening in said shank portion for effecting positive rotation of said fastening means relative to said shank portion as selected, and plural prong elements formed on said fastening means and disposed wholly within the axial limits of said shank portion to engage and 15 penetrate fabric thrust into said hollow interior thereof as said fastening means is rotated.
9. The combination as set forth in claim 8 in which said means for locking said fastening means in said opening comprises a resilient annular split ring member 20 adapted to be inserted in the said annular opening and having suitable surface means interferingly aligned with said fastening means for holding such in place.
10. A button device, for use as a garment fastener comprising, a body portion, a hollow shank portion extending outwardly of said body portion, means interconnecting said body and shank portions in a manner permitting the same to rotate relative to each other, fabric engaging prong means fastened to said body portion and extending into the hollow interior of said shank 25 portion, said prong means being adapted upon relative rotation between said body and shank portions to engage fabric thrust into the interior of said shank portion and thereby fasten the button device to said fabric, and means locking said prong means against axial displacement.
- 30 11. In a button fastener, the combination comprising: a button body having a central recess therein, said recess including side and bottom walls with a projecting bead formed on said side wall and said bottom wall having a pair of blind hole openings therein; a hollow shank portion fitted in said recess, having a side wall including a central depression positioned for locking engagement with said projecting bead to prevent axial displacement between said body and said shank, having a base portion with a frusto-conical bore therein, and further having a 35 pair of slotted apertures in the central bore thereof; and a fastening ring mounted wholly within said shank portion, including a pair of prongs, a base having a flared wall fitted against said frusto-conical bore to prevent axial displacement between said shank and said fastening ring, 40 said fastening ring base further having a pair of depending fingers extending into said blind hole openings to prevent rotational movement between said body and said fastening ring, and a detent positioned on said fastening ring to engage one of said slotted apertures in said shank, 45 whereby relative rotation between said shank and said fastening ring displaces said fastening ring from its inoperative position wherein it is locked by engagement of said detent with one of said slotted apertures to an operative position wherein it is locked by engagement of said 50 detent with the other of said slotted apertures.
